E. L. BURKY

GOLF BAG SUPPORT

Filed April 16, 1926

Edward L. Basye. INVENTOR.

BY
Herbert Loring & Son, Attorneys

UNITED STATES PATENT OFFICE.

EDWARD L. BURKY, OF DREXEL HILL, PENNSYLVANIA, ASSIGNOR OF ONE-FOURTH
TO HARLEIGH B. BURKY, OF GLOUCESTER, NEW JERSEY.

GOLF-BAG SUPPORT.

Application filed April 16, 1926. Serial No. 102,389.

My invention relates to a new and useful supporting device for golf bags and the like, adapted to be firmly and rigidly secured around the outer bottom periphery thereof, whereby said bag will be maintained in an upright or vertical position, by a slight tapping or ramming action, which will drive or implant the ends of the spurs of said supporting device into engagement with the sod, turf or fairway on which it is desired to position the golf bag, while the golfer is taking his stance or making a shot.

By my novel construction of a golf bag support, it is possible easily and instantly to set and maintain a golf bag in an upright or vertical position, thus enabling the golfer to select, take out and replace a desired golf club, without having to stoop down to pick up the golf bag, which would otherwise be lying horizontally on the turf, and without having to hold the bag upright while a club is being thus withdrawn or replaced.

By my novel construction it is further possible to fix and maintain the golf bag in an upright position, regardless of the condition, grade or inclination of the fairway on which it is desired to place such bag, as will be more apparent.

My novel construction of a golf bag support is further highly advantageous in that it is very strong and durable and can be produced at a minimum cost, as its construction and assembly are very simple and easily effected. It is also compact and capable of being so secured to the golf bag, that when in use, it does not constitute a separate additional article that has to be transported around the links, as would be the case if some extraneous support, separate and independent of the bag were employed.

My novel construction of a golf bag support can be manufactured and sold in the open market as a separate article altogether independent of the golf bag construction per se, and at the same time is readily attachable to and detachable from the same, by the user, thus rendering it possible to apply said support to existing golf bags.

With the above ends in view, my invention consists of a novel golf bag support comprising an annular band of suitable

width and thickness and adjustable as to length or circumference, formed of strong flexible material, preferably leather, canvas or the like, which is adapted to encircle the bottom of the golf bag and which is adapted to be firmly and rigidly and yet detachably secured thereto. On said annular band or belt element are carried a plurality of pendant spurs, preferably made of some strong, inexpensive sheet metal, such as iron, steel or the like, which are rigidly and permanently secured to the band or belt at spaced intervals throughout the length thereof, and which extend downwardly below the bottom of the bag and terminate in tapering pointed ends adapted to be implanted or driven into the sod, turf or fairway by a slight ramming action, firmly to engage the same, thus providing a strong and secure anchorage for the golf bag supported thereby.

From the main body portion of each of the spurs at a point substantially midway of the height thereof, is stamped out an upwardly projecting tongue, projecting inwardly and upwardly therefrom, which tongue interlocks with the bottom of the bag, thus eliminating any possibility of the band sliding upwardly along the body of the bag, when the same is rammed or pushed downwardly in driving the spurs into the turf, sod or fairway. As the bottom end of the golf bag may flare a little or be of a slightly larger circumference than the body portion around which the band or element is tightly fitted and secured, it will be impossible for the band to slip over the bottom end when an upward pull is exerted in withdrawing the spurs from the fairway, when it is desired to "uproot" the golf bag and "implant" the same in another locality as the game progresses. Thus it is evident that my novel supporting device is maintained securely in position upon the bag at all times.

For the purpose of illustrating my invention, I have shown in the accompanying drawings forms thereof which are at present preferred by me, since they will give in practice satisfactory and reliable results, although it is to be understood that the various instrumentalities of which my invention

consists can be variously arranged and organized and that my invention is not limited to the precise arrangement and organization of these instrumentalities as herein shown and described.

Referring to the drawings,

Figure 1 represents a perspective view of a golf bag of any conventional type the same being equipped with a golf bag support embodying my invention.

Figure 2 represents a plan view on an enlarged scale of the golf bag support detached.

Figure 3 represents, on an enlarged scale, a vertical sectional view, on line 3—3 of Figure 1.

Figure 4 represents a front perspective view on an enlarged scale of a portion of my novel support, showing the manner in which the spurs are secured to and carried by the annular band.

Figure 5 represents a rear perspective view on an enlarged scale of the same portion of my novel support shown in Figure 4, showing the inner tongue or lip portion stamped out of the body portion of the spur.

Referring to the drawings, in which like reference characters indicate like parts, 1 designates a golf bag of any conventional type, the bottom thereof being equipped with my novel supporting device. 2 designates an annular band or belt, element, preferably formed of leather, canvas, or other suitable strong and flexible material carrying a plurality of pendant spurs 3. The band 2 of any suitable dimensions, is also provided with the buckle 4 and the holes 5, whereby it is possible to vary the circumference of the band and to secure and tighten the same around golf bags of different sizes. Each of the spurs 3 is preferably formed of sheet metal, such as iron, steel or the like, the upper portion of which is so bent over on itself and then downwardly so as to form an inverted U shaped portion, (see Figures 3, 4 and 5,) consisting of the rear wall 6, the top wall 7 and the front wall 8. The body portion of the spur is further slightly bent forwardly or offset as at 17. (See Figures 3 and 5). Through the inverted U shaped upper portion of the spurs 3 is passed the annular band or belt element 2, to which the spurs are rigidly secured by means of the rivets 15 or the like, passing through the aligning holes 14 in the front wall 6 and rear wall 8 respectively, and through the band or belt thus securing the spurs to said band in a rigid and permanent manner. From the body portion of each of the spurs 3 and preferably from the bent portion 17 thereof, is stamped out a tongue or lip portion 11, which projects inwardly and upwardly, at an angle to the lower vertical body portion 9 of the spur. This

tongue 11 serves to support and engage the bottom 12 of the bag as will be hereinafter described in detail. The lower body portion 9 of the spurs 3 is tapered and terminates in the pointed end 10 which is adapted to be driven into or implanted in the turf or fairway 13 when it is desired to stand the bag in an upright position, as will be seen in Figures 1 and 3.

In order to stand a golf bag equipped with my novel support, in an upright position, it is merely necessary to force the same slightly downwardly, whereupon the tapering pointed ends 10 of the spurs 3 become firmly embedded in the turf or fairway, thus providing a secure anchorage for the golf bag, the tongue or lip portion 11 serving to support and engage the bottom pendant flange 12 of the bag. (See Fig. 3.) Thus, with the annular peripheral bottom flange 12 of the bag 1, engaged or locked between the bent portion 17 and the tongues 11, it will be impossible for the band 2 carrying the spurs 3 to slide upwardly along the body of the bag when the spurs are rammed downwardly into engagement with the turf. Since the tongues 11 project at an angle to the body portion of the spurs 3, they serve as a stop to prevent the same from sinking too deep into the fairway so that the golf bag may be "uprooted" and the spurs withdrawn from engagement with the sod at all times with great ease and facility.

When the golfer desires to "uproot" the bag thus implanted or anchored, preparatory to following the ball and taking his stance for the next shot, it is merely necessary to exert an upward pull on the handle 16 or any other portion of the bag. As the bottom annular peripheral flange 12 is flared outwardly, as will be understood from Figure 3, making the bottom circumference of the bag slightly larger than the periphery of the body portion around which the band 2 is snugly fitted and secured, it will obviously be impossible for said band to slip over the bottom of the bag, when an upward pull is exerted thereupon, in effecting a disengagement of the spurs 3 from the turf 13.

Figure 2 shows a preferred arrangement of the spurs 3 along the circumference of the band 2, but it is obvious that any desired number of spurs or any suitable arrangement thereof may be adopted, and they are preferably spaced upon said band at substantially equal distances from each other, which will provide sufficient anchorage for the golf bag.

A golf bag thus supported by the spurs engaging the turf, can thus be set or "implanted" in any particular spot, regardless of the surface condition, or grade of the turf, without any adjustment of the supporting means, since said spurs can be forced into

engagement with the turf into which they are rammed, regardless of irregularities on the upper surface thereof.

Having thus described my invention, what I claim as new and desire to secure by Letters Patent, is:—

1. In a device of the character stated, a detachable and flexible strap and complementary buckle, adapted to engage the bottom 10 of a golf bag, offset pendant spurs rigidly secured to said strap and upwardly and inwardly projecting tongues, pressed out from the body of said spurs and adapted to engage the bottom flange of the bag.
- 15 2. A golf bag support of the character stated, comprising an annular band adapted to be tightened around a golf bag, a plurality of spaced apart pendant spurs carried by said band, each of said spurs comprising 20 an inverted U shaped upper portion adapted to inclose said band, a lower pointed portion

adapted to be driven into the turf and tongues carried by the body of said spurs and projecting inwardly and upwardly at an angle thereto, said tongues being adapted 25 to engage and support the annular peripheral bottom flange of the bag, and fastening means for permanently and rigidly securing said spurs to said band.

3. A golf bag support comprising an annular, flexible band adapted to be adjustably tightened around the flanged bottom of a golf bag, a plurality of spaced rigid, pendant spurs fixed to said band and each having a lower pointed portion, each having 35 a tongue extended from said lower portion of a spur and projecting inwardly and upwardly at an angle thereto, said tongues being adapted to engage and support the annular peripheral bottom flange of the bag.

EDWARD L. BURKY.
